(74) Attorney, Agent, or Firm — Patterson Thuente
Pedersen, P.A.(57) **CLAIM**

We claim the ornamental design for a surgical contact glass, as shown and described.

DESCRIPTION

FIG. 1 is a top perspective view of a surgical contact glass. FIG. 2 is a bottom perspective view of a surgical contact glass depicted in FIG. 1.

FIG. 3 is a front elevational view of a surgical contact glass depicted in FIG. 1.

FIG. 4 is a side elevational view of a surgical contact glass depicted in FIG. 1.

FIG. 5 is a back elevational view of a surgical contact glass depicted in FIG. 1.

FIG. 6 is a bottom plan view of a surgical contact glass depicted in FIG. 1; and,

FIG. 7 is a top plan view of a surgical contact glass depicted in FIG. 1.

Portions of the surgical contact glass depicted in broken lines form no part of the claimed design.
